S. D. Arnold of New Britain Conn. DES. 2384

Assignor to

S. H. Corbin of Somersbury, J. C. Shurley Company of Amsterdam No. York
Letters Patent No. 2384, Dated Aug. 14, 1866

Design for Coffin Trimmings.

The schedule referred to in this Letters Patent and making part of the same;

To all whom it may concern:

Be it known that S. D. Arnold of New Britain
Hartford County, and State of Connecticut, have invented a new
Design for Coffin Trimmings; and I do hereby declare that the
following is a full, clear and exact description thereof which will
enable others skilled in the art to make and use the same reference
being had to the accompanying drawing forming part of this specification.

The present invention consists of an ornamental plate
to be used upon coffins and other burial cases, about the heads of
the screws by which the parts of such cases are secured together, and
in accompanying plate my new Design is illustrated, the,

Figure being a photographic view of the same.

A, in the plate represents the plate which at its centre has an ap-
erture B, to receive the screw about which it is to be placed and is
ornamented upon each side of such aperture with a rose C,
beyond each of which are rose leaves D, constituting the ends of the
plate.

I claim as new and desire to secure by Letters Patent,
The Design herein described and illustrated in the
accompanying plate.

Witnessed

Chas. Peck
